UNITED STATES PATENT OFFICE

BURCHARD THOENS, OF NEW ORLEANS, LOUISIANA.

VACUUM-PUMP.

SPECIFICATION forming part of Letters Patent No. 329,241, dated October 27, 1885.

Application filed December 27, 1884. Serial No. 151,354. (No model.)

To all whom it may concern:

Be it known that I, BURCHARD THOENS, a subject of the Emperor of Germany, residing at New Orleans, Louisiana, have invented new and useful Improvements in Vacuum-Pumps, of which the following is a specification.

My invention relates to apparatus for producing high vacua, and belongs to that class of such apparatus wherein the movement of a fluid or its removal from the vessel to be exhausted is caused by the flow of a body of liquid in its vicinity, and its object is to furnish an apparatus capable of speedily and reliably producing vacua of a high degree of attenuation.

The most common type of apparatus of this general class is the well-known Sprengel drop-pump, in which the liquid used is allowed to drop through a punched or strangulated opening from its reservoir, through the drop-tube, and past the opening leading from the vessel to be exhausted to the drop-tube. This liquid falls slowly in drops, and with such speed and force only as are due to gravity. The action therefore is necessarily slow, it requiring, even with the most approved forms of such drop-pumps, and as improved during the past few years, several hours to produce a high degree of exhaustion in a small incandescent 30 electric-lamp globe whose contents are only six to eight cubic inches. This has also confined the use of such pumps within narrow limits, and for small objects, only such as Geissler tubes, incandescent lamps, Crook's 35 radiometer, &c. In order, therefore, to produce a pump of much more speedy action, and adapted to be used with much larger objects when desired, I prefer to use what may be termed simply an "ejector-pump," wherein the 40 point of communication of the vessel to be exhausted is itself contracted, and is entirely surrounded with a column of the exhausting-fluid used, which is itself under a pressure or force exerted upon it by the force-pump used 45 to keep it in circulation. In order to attain still greater rapidity of action, several injectors are used—one connected to the vessel to be exhausted, the others, which may be termed "auxiliary injectors," connected each to the 50 discharge-pipe of the preceding one at a point below the discharge-nozzle of the latter, and above a point which represents the baromet-

ric height of the liquid used. This may be better understood by reference to the drawing, in which the figure is a view, partly in section and partly in elevation, of an apparatus embodying my invention.

In the drawing, the reference-numeral 4 indicates the supply-tank for the liquid used, from which the liquid is taken and forced 60 through the exhausting apparatus by means of the pump 2, of any suitable construction.

9 is the drop pipe or tube of the first or main ejector, upon which is secured or in which is formed the contracted portion 12, in which is 65 secured the conical or contracted nozzle 13, affixed to the pipe 8, which leads to and communicates with the vessel to be exhausted. The nozzle 13 is of such size relatively to the portion of 12 in which it sets that a concentric space is formed around it within 12. Communicative thereto from the branch 5, leading from the pipe 5, through which the liquid used is forced by the pump 2, is formed an enlargement, 14, so that the fluid is discharged 70 from 5 around 13 in the shape of a moving 75 hollow cone. This action, it is known, will produce a suctional effect in the pipe 8, drawing therefrom the fluid in the vessel it is connected with, and discharging it with the moving liquid in the pipe 9. This insures a greater rapidity of action than in the ordinary Sprengel pump, where drops falling act as minute pistons carrying a small modicum of air only before them.

In order to attain greater rapidity of action, and also free the air that becomes mingled with it prior to its discharge into 4, auxiliary ejectors or pumps to any desired number may be used, one such being shown in the drawing. This communicates with the drop-pipe 9 at a point below the discharge-nozzle 13 and contraction 12 and above the point of barometric height of the fluid used, which point, of course, will vary, according to the fluid used, 95 from thirty-one inches for mercury to thirty-three feet for water, or a greater height if a still lighter liquid, as oil, be used.

The construction of the ejector portion is similar to that already described, and it is 100 supplied with the necessary liquid by a branch, 5, from 5.

The drop-tube 9 of the first or main ejector should end below the normal level of the liq-

uid in the tank 4, so as to be sealed thereby against the ingress of air, while it is preferable that the drop-tube 9 of the auxiliary ejector should end above such level, in order to 5 discharge into the open air, and it may be provided with an outwardly-opening check-valve, in order to close automatically against ingress of air. If several auxiliary ejector-pumps are used, each is connected to the preceding one, 10 as the auxiliary one here shown is connected to the preceding one, and preferably the drop-tubes of all, excepting the last, should end below the level of the liquid, as does 9.

Any desired liquid—mercury, oil, glycerine, 15 water, &c.—may be used, the only variations needed being those of size due to the different densities and gravities of the liquids. It is evident that the connecting-pipes 10, the auxiliary ejectors, and the supply-tubes 5^a may 20 be provided with suitable stop-cocks, so that any desired number only of a series of such auxiliaries may be used.

This arrangement produces a vacuum-producing apparatus speedy and reliable in operation for exhausting the globes of incandescent lamps, evaporating and concentrating liquids, producing rapid evaporation for the production of low temperatures, and various other purposes.

30 Each ejector-pump does its share of work, and by making a partial vacuum below the falling column of its predecessor adds to the efficiency of such predecessor, while the air or vapor which has become mingled with the liquid during the passage of the latter through 35 the main ejector-pump is removed therefrom by the action of the auxiliary ejector-pumps.

The method embodied of treating or using the liquid employed by subjecting it itself to the action of a vacuum apparatus after its passage through the main pump and before it returns thereto is not now herein claimed, as it will form the subject of a separate application. 40

Having thus described my invention, what I claim is—

45 1. In apparatus for producing high vaca, the combination of a main ejector-pump, to which the vessel to be exhausted is connected, and one or more auxiliary ejector-pumps, each having its suction-pipe connected to the drop or discharge pipe of the preceding ejector-pump, substantially as described.

2. In apparatus for producing high vaca, the combination of a main ejector and one or more auxiliary ejectors, each connected with 50 the discharge or drop pipe of the preceding ejector at a point below the discharge-nozzle thereof and above a point representing the barometric height of a column of the fluid used, substantially as described.

55 3. In an apparatus for producing high vaca, the combination of a main ejector-pump, one or more auxiliary ejector-pumps, connected as described, supply tubes or branches leading thereto, a reservoir or tank for the fluid, 60 and a pump or forcing apparatus for supplying the liquid therethrough under pressure, substantially as described.

In testimony whereof I affix my signature in presence of two witnesses.

BURCHARD THOENS.
